ATTORNEY,

UNITED STATES PATENT OFFICE.

FERDINAND PHILIPS, OF PHILADELPHIA, PENNSYLVANIA, ASSIGNOR TO PHILIPS PRESSED STEEL PULLEY WORKS, OF PHILADELPHIA, PENNSYLVANIA, A CORPORATION OF PENNSYLVANIA.

SHEET-METAL PULLEY CONSTRUCTION.

No. 888,845.

Specification of Letters Patent.

Patented May 26, 1908.

Application filed December 1, 1904. Serial No. 235,011.

To all whom it may concern:

Be it known that I, FERDINAND PHILIPS, a subject of the Emperor of Germany, residing in the city and county of Philadelphia, in the 5 State of Pennsylvania, have invented a certain new and useful Improvement in Sheet-Metal Pulley Construction, of which the following is a true and exact description, reference being had to the accompanying drawings, which form a part thereof.

My invention relates to sheet metal pulleys and has for its object to provide for stiffening and strengthening the union between the rim and the spokes which in pulleys of this class 15 has been found very likely to be weak.

Generally speaking, my invention consists in inserting between the inwardly extending flanges of sheet metal to which the spokes are secured a ring of metal which not only adds 20 its own strength to that of the sheet metal flanges, but also stiffens and strengthens the flange as a whole owing to the separation of the sheet metal flanges. By preference the outer edge of this inserted ring of metal is 25 enlarged and formed with fillets which serve to support and give proper form to the fillets formed between the sheet metal forming a part of the rim proper and that portion of the metal which is turned inward to form the 30 flange.

Reference is now had to the drawings which illustrate my invention and in which

Figure 1, is a side view of a pulley of the general character to which my invention is 35 adapted to be applied. Fig. 2, is a cross-section taken as on the line 2—2, of Fig. 1, and Figs. 3, 4 and 5, similar cross-sections showing modifications in the form and character of the inserted metal ring.

40 A indicates the outer surface of the sheet metal pulley which, as shown, is a two-ply pulley, the under thickness of the sheet metal being indicated at B, and the flange edges of the pulley at C C. At E, E, the 45 under plies B, of the pulley rim are bent in to form the flanges D, D, these flanges not being brought together but contacting with a central metallic ring F the periphery of which bears against the outer ply of the rim, and 50 which, by preference, is formed with an en-

larged head F', filleted at F², F², the fillets or curves E, E, contacting with the fillets of the ring as shown.

G, G, etc., are inserted metal pieces abutted against the flange of the rim and to which 55 as well as to the flange the spokes H, H, of the pulley are secured as by rivets I, I' and I².

J indicates the hub of the pulley to which the inner end of the spokes are secured.

In the construction shown in Fig. 3, the 60 inserted ring of metal indicated at F³, is shown as being made by folding sheet metal into the general form of the inserted ring F, of Fig. 2.

In Fig. 4, the inserted ring, here indicated 65 at F⁴ is made of two sections F⁵, F⁵, of metal abutted against each other and with their upper ends curved outward to form the fillets F², while in Fig. 5, the inserted ring, here indicated at F⁶, is a plain rectangular bar of 70 metal without enlarged head or fillets.

By preference the sheet metal of the rim while still straight is brought to the cross-sectional form shown in Fig. 2, and a straight bar of the cross section of the bar F inserted 75 between the inwardly bent flanges, and then the rim and inserted bar bent or curved to semi-circular shape so as to form one-half of a pulley rim, the bending being preferably accomplished by mechanism such as is described in my prior patent No. 651,053 of June 5th, 1900.

Having now described my invention, what 80 I claim as new and desire to secure by Letters Patent is,

1. A sheet metal pulley rim having a sheet metal rim portion proper consisting of an outer ply of sheet metal and an inner ply of sheet metal bearing against the inner surface of the outer ply, and a flange portion consisting of radially in-turned portions of the inner ply, and a metal ring interposed between and in close contact with said in-turned portions, and bearing against the inner surface of the outer ply. 90

2. A sheet metal pulley rim having an outer rim ply of sheet metal, an inner rim ply bearing against the outer ply and consisting of portions of the outer ply material doubled back, and an internal flange or web consist- 100

ing of inturned portions of the inner ply and a reinforcing ring interposed between and in close contact with said inturned portions and bearing against the outer ply.

- 5 3. A sheet metal pulley rim having an inwardly extending central rib formed by two flanges of the sheet metal of which the rim is

made and in close contact therewith an interposed ring of metal having its outer edge enlarged and formed with fillets F^1 , F^2 .

FERDINAND PHILIPS.
